DEVICE FOR ADJUSTING CYLINDER HONES
AND THE LIKEWilliam E. Heuer, Toledo, Ohio, assignor to The
Hall Manufacturing Company, Toledo, Ohio, a
corporation of Ohio

Application January 10, 1929. Serial No. 331,499

2 Claims. (Cl. 51—184.3)

This invention relates to a device for adjusting cylinder hones, with special reference to the radial adjustment of the stone carriers so that they may be accurately fitted to the work in hand, and 5 may, if desired, be readjusted during the progress of the work.

In the present adaptation of the invention, it is associated with a cylinder hone in which the stone carriers are supported by a hollow rotatable body 10 and are adjustable radially by the longitudinal adjustment of a spindle disposed axially of a tubular shank, the latter being operatively connected in driving relation to the body.

The general object of the invention is to provide improved means for adjusting the relation of the adjusting spindle to the shank connected with the body, and in this connection, provision is made for determining the extent of the adjustment with the utmost precision by means constructed on the principle of a micrometer.

The specific construction of the invention in its preferred embodiment, together with its mode of operation, will be more particularly explained in connection with the accompanying drawing, 25 which illustrates the same in detail.

In the drawing:

Figure 1 is a central longitudinal sectional view of the invention.

Figure 2 is a view partly in elevation and partly in section of the mechanism illustrated in the upper part of Figure 1.

Figure 3 is a transverse section taken on the line 3—3 of Figure 1.

Figure 4 is a transverse section taken on the line 4—4 of Figure 2.

Figure 5 is a prospective view of the clutch members by means of which the device is set for a predetermined adjustment.

The cylinder hone, in connection with which the invention is illustrated, comprises a hollow body 1 on which the stone carriers 2 are supported for radial adjustment. This adjustment is effected by the projection of radial pins 3, which are mounted in the body with their outer 40 ends projecting into a recess 4 of the stone carrier, thus providing a floating support for the latter. The outward projection of the pins 3 is effected by advancing a cam member 5 within the body 1, this cam member being provided with inclined 45 surfaces engaging the inner ends of the pins 3. The upper end of the cam member 5 is normally held in engagement with a plug 6 which has a threaded connection with the upper portion of the body 1 and may be rotated to advance the 50 cam member 5 for expanding the hone. The plug

6, in the present instance, is provided with a polygonal opening adapted to receive the correspondingly shaped end portion 7 of a spindle 8.

The upper end of the body 1 is formed with a head 9 which is cupped to receive the rounded head 10 of a tubular shank 11 through which the spindle 8 extends. The head 9 is formed at its end with radial slots 12 for receiving pins 13 which project from the head 10 to establish a driving connection. This connection is maintained by a washer 14 which fits the upper part of the head 10 and is held within a cap 15 which is secured to the upper end of the head 9 and retained thereon by means of a lock nut 16. Thus it will be seen that the shank 11 has a limited 70 universal movement with relation to the body 1 while its driving connection with the latter is maintained. The spindle 8 normally rotates with the shank 11 during the honing operation, but for the purpose of expanding the hone, when occasion requires, the shank 11, by means herein-after described, may be rotated relatively to the spindle 8 and plug 6, thereby advancing the latter and also the cam member 5.

The shank 11 is adapted to be driven from a 80 chuck or sleeve 17, the lower end of which is provided with a bayonet slot 18 for receiving a pin 19 projecting laterally from the upper end of the shank. The upper end of the sleeve 17 is internally threaded to receive a corresponding 85 threaded portion 20 of the driving member 21, the latter being formed with a peripheral flange 22 which seats against the upper end of the sleeve.

The upper portion 23 of the spindle 8 is polygonal and carries a clutch member 24 which is rotatably mounted within the sleeve 17 and is held against longitudinal movement in the sleeve by a pin or screw 25 extending inwardly from the sleeve into a circumferential channel 26 90 formed in the clutch member. The upper face of the clutch member 24 is formed with teeth 27 which are adapted to interlock with teeth 28 formed on the opposed face of a complementary clutch member 29. The clutch member 29 has 100 a limited longitudinal and rotational movement within the sleeve 17 but is normally held in interlocking engagement with the member 24 by means of a spring 30 interposed between the upper face of the member 29 and the lower end of 105 the driving member 21.

A pin 31 is secured diametrically in the clutch member 29 and extends outwardly through a slot 32 in the sleeve 17. This slot is wide enough to permit the member 29 to be raised far enough 110

to disengage the teeth 27 and 28, permitting a partial rotation of the member 29 while the member 24 remains stationary, the extent of such movement being limited by the length of the 5 slot 32, which preferably extends for about one third of the circumference of the sleeve.

The sleeve 17 is surrounded by a drum 33 which receives the outer end of the pin 31, thus securing the drum to the member 29. The sleeve 10 17 is also provided with a hole 38 so that the pin 31 may be knocked out when it is desired to disassemble the device.

In the normal operation of the hone, the member 21 is continuously driven, thereby driving the 15 sleeve 17, the shank 11 and the body 1 on which the stone carriers 2 are supported. The spindle 8 is adapted to be driven by the clutch member 24 which in turn is driven by the member 29. If the pin 31 is engaged by the rear end of the 20 slot 29, it follows that the spindle 8, the plug 6 and the cam member 5 will be driven in unison with the body 1. If, however, the pin 31 is not at the rear end of the slot 29 the spindle 8 will remain stationary while the sleeve 17 advances 25 until the end of the slot engages the pin. This partial relative rotation causes the plug 6 to rotate within the body to advance the cam member 5 and expand the hone.

When it is desired to expand the hone, therefore, the drum 33 may be raised, together with the clutch member 29 and partially rotated with 30 relation to the member 24. For the purpose of determining this adjustment accurately, the lower edge of the drum 33 is provided with a scale 34, and a collar 35, which is secured by a set screw 36 to the sleeve 17 below the drum 33, is provided with a shoulder 37, with reference to which the graduations of the scale 34 may be gaged. In effecting the expansion of the hone, the drum 33 35 and clutch member 29 may be advanced the distance of one of the teeth 28, as indicated by one space on the scale 34, or it may be advanced for the entire length of the slot 32. Then in order to positively insure the expansion of the hone, 40 the drum 33 may be gripped by a brake-band, indicated at 39, while the power is applied to the member 21. This will prevent the rotation of the spindle 8 until the rear end of the slot en-

gages the pin 31, thus effecting the desired expansion, after which the shank 11, the spindle 8 and all parts of the hone rotate together.

From the foregoing description, it will be seen that I have provided a device by which predetermined adjustment of the hone may be effected quickly with the utmost accuracy. While I have described the hone as power driven, whereby it is particularly adapted for production work, it is apparent that the same construction may be used in reconditioning work and may, in fact, be used in connection with any mechanism wherein it is desired to effect a relative rotational adjustment of one member with respect to another, which is co-axial therewith.

What I claim is:

1. In a cylinder hone driving and adjusting mechanism, a sleeve constituting a drive member, a hollow shank driven thereby, a clutch member within the sleeve guided for rotation relative thereto, a spindle keyed to said clutch member and extending through said shank, a co-operating clutch member in said sleeve normally rotatable in unison therewith and held in engagement with the first mentioned clutch member, but movable for a limited distance out of engagement with said first mentioned clutch member and forwardly with reference to the sleeve, whereby the latter may then advance through a partial rotation without driving said spindle. 95

2. In combination, a rotatable sleeve, co-operating clutch members carried by the sleeve, a spindle keyed to one of said clutch members, a connection between one of said clutch members and said sleeve including a circumferential groove 110 with a pin engaging the same and permitting relative rotation of the sleeve and clutch member but preventing relative longitudinal movement thereof, a connection between the other clutch member and the sleeve including a radial pin and an arcuate slot, the latter being wide enough to permit separation of the clutch members and long enough to permit a partial relative rotation only of the sleeve and clutch member, whereby the latter may be set to permit an initial partial rotation of the sleeve when the latter is driven before the clutch and spindle begin to rotate. 115
